(57) CLAIM

The ornamental design for a sport display, as shown and described.

DESCRIPTION

FIG. 1 is a front elevational view of an ornamental design for a sport display in a deployed manner of use; and, FIG. 2 is a front elevational view of the sport display of FIG. 1 in a folded manner of use.

The dashed lines are for the purpose of illustrating portions of the sport display that form no part of the claimed design.
